UNITED STATES PATENT OFFICE.

GEORGE W. THOMPSON, OF PITTSBURG, PENNSYLVANIA.

STREET-RAILWAY SWITCH.

SPECIFICATION forming part of Letters Patent No. 739,742, dated September 22, 1903.

Application filed December 2, 1902. Serial No. 133,535. (No model.)

To all whom it may concern:

Be it known that I, GEORGE W. THOMPSON, a citizen of the United States of America, residing at Pittsburg, in the county of Allegheny and State of Pennsylvania, have invented certain new and useful Improvements in Street-Railway Switches, of which the following is a specification, reference being had therein to the accompanying drawings.

10 This invention relates to certain new and useful improvements in switches; and the invention has for its object to provide a switch which may be conveniently and easily operated by the motorman from the car.

15 The invention is particularly adapted to be used in connection with street-railway switches, and has for its further object to provide a normally open switch, whereby an uninterrupted travel on the main line may be obtained; and the invention further resides in means for automatically opening the switch after a car has passed onto the side track, so that the main line will again be in position for traffic of following cars.

25 Briefly described, the invention comprises, in connection with a pivoted switch-tongue, a cable which is connected to the tongue and is extended over pulleys suitably arranged in the road-bed and pivotally connected at its one end to the trip located adjacent to one of the rails, whereby it may be engaged by mechanism suspended from the car. The other end of the cable is likewise pivotally connected to the trip located adjacent to one 30 of the rails of the track, whereby it may be engaged by the car mechanism for operating the cable to close the switch. All of this construction will be hereinafter more fully described, and specifically pointed out in the 35 claim.

40 In describing the invention in detail reference is had to the accompanying drawings, forming a part of this specification, and wherein like numerals of reference indicate 45 like parts throughout the several views, in which—

Figure 1 is a top plan view of my improved switch, the casing for the operating-cable being removed. Fig. 2 is a side elevation of the 50 same. Fig. 3 is a transverse vertical sectional view. Fig. 4 is a central vertical sectional view of the preferred form of operating-shaft

carried by the car. Fig. 5 is a side elevation of the same.

In the accompanying drawings, 1 and 2 indicate the rails of the main track; 3 and 4, the rails of the side track, and 5 the pivoted switch-tongue, which forms a part of the side-track rail 3. In practice, the switch is normally open, in which position it is shown in Fig. 1 of the drawings. The invention resides particularly in the means for closing the switch-tongue, so as to permit the car or cars to pass onto the side track when desired. To accomplish this, I employ a cord, cable, chain, or like flexible connection 6, the one end of which is attached to the trip 7, pivoted at a point adjacent to the main rail 2, preferably underneath this rail, where it may be engaged by mechanism supported from the car. This cord, cable, or other flexible connection is passed through a casing 8, located outside the rail 2, and in which are arranged pulleys 9 10, the former placed adjacent to the trip 7 and the latter placed opposite to the switch-tongue 75

5. The cord, cable, or other flexible connection is passed through underneath the rail 2 after being carried over the pulley 10 and is conducted through a casing 11, arranged between the main rails on the track and alongside of the rail 3. In this casing the flexible connection is conducted over a series of pulleys 12 and is carried underneath the rail 1 to a point some distance beyond said rail and over the pulley 14, then underneath the side-track rail 3, over the pulley 15, and is connected to the pivoted trip 16, located adjacent to said rail 3 and preferably underneath the same. In order to operate the switch-tongue, the flexible connection is connected 80 thereto, which may be by a bolt or pin 17 or other suitable connection. The trips are adapted to be engaged by mechanism suspended from the car, which preferably comprises a stem or arm 18, to which the shoe 19 85 is connected by means of the stiff coil-spring 20. I provide this spring-shoe so that in case the switch-point should be obstructed the shoe will be permitted to spring past the trip without bringing undue strain upon the 90 flexible connection, the spring being of sufficient strength so that operation of the switch-point will take place in event of no obstruction being presented thereto.

Having fully described my invention, what I claim as new, and desire to secure by Letters Patent, is—

In a switch, the combination with the main and the side track rails, and a switch-tongue pivoted to the ends of one of said side rails, of a casing located outside of the main side rails and extending parallel thereof, pulleys arranged in said casing, a casing arranged between the main rails and extending along the side of the side-track rails, the last-named casing passing underneath the other main-track rails, pulleys arranged in the said casing, a flexible connection secured to a joint in the first-named casing and passing over the pulleys arranged therein, then passing

beneath the said main track to the other said casing and passing over the pulleys arranged therein, a trip pivoted adjacent the end of the first-named casing and connected to the end of the flexible connection, a like trip pivoted adjacent the other said casing and connected to the other end of the said flexible connection, and means for engagement with said trips to actuate the flexible connection and move the switch-tongue, substantially as described.

In testimony whereof I affix my signature in the presence of two witnesses.

GEORGE W. THOMPSON.
